UNITED STATES PATENT OFFICE.

JOHN H. VINTON, OF BOSTON, MASSACHUSETTS, ASSIGNOR TO THE TRIMONT
MANUFACTURING COMPANY, OF PORTLAND, MAINE.

DESIGN FOR JAWS OF A PIPE-WRENCH.

SPECIFICATION forming part of Design No. 19,168, dated June 18, 1889.

Application filed December 26, 1888. Serial No. 294,698. Term of patent 14 years.

To all whom it may concern:

Be it known that I, JOHN H. VINTON, a citizen of the United States, residing at Boston, in the county of Suffolk and State of Massachusetts, have invented and produced a new and original Design for Jaws of Pipe-Wrenches, of which the following is a specification, reference being had to the accompanying drawing, forming part thereof.

10 The drawing shows, in elevation, a wrench containing my design.

The leading feature of my design consists in an undulating curvilinear screw-thread, as opposed to or distinguished from a rectilinear or rectangular screw-thread applied to the shank of the movable jaw of a wrench.

15 The handle *a*, fixed jaw *b*, and nut *c* may

be of approved shape. The movable jaw *d* has applied to its shank *e* screw-threads *f* of undulating or curvilinear outline, as distinguished from the rectilinear or rectangular screw-threads commonly used. 20

What I claim is—

The design for wrenches herein shown and described, the same consisting of the movable 25 jaw having a shank provided with undulating or curvilinear screw-threads, as set forth.

In testimony whereof I have signed my name to this specification in the presence of two subscribing witnesses.

JOHN H. VINTON.
